DUPLEX FACSIMILE TRANSCEIVER

William G. H. Finch, Newtown, Conn.

Application February 10, 1940, Serial No. 318,230

8 Claims. (Cl. 178—13)

This invention relates to novel apparatus for and methods of transmitting and receiving signals and more particularly relates to novel apparatus for and methods of visual broadcasting and reception.

This specific invention is concerned with the combination in a single, light-weight unitary simplified mechanism of both the facsimile transmission and receiving apparatus. The duplex device thereby formed is arranged so that the more important portions of the operating mechanism are therefore utilized both for transmission and reception of facsimile signals and for the operation of the various mechanical portions thereof, thus resulting in an appreciable decrease in weight and complexity of the system. The consequent reduction in weight and simplification in operation makes the apparatus of the present invention peculiarly adaptable for portable facsimile units wherein both transmission and reception of facsimile signals is desirable.

Thus, for instance, in airplanes, where additional apparatus results in a decrease in payload, it becomes exceedingly important that duplication of mechanical as well as electrical apparatus be avoided, and that the various reception and transmission elements be, as far as possible, operable through or by the same means.

By the use of this simplified duplex device, therefore, instructions or other information may be transmitted visually,—that is, necessary charts and other information best transmitted by visual means may readily be received by the operator of the airplane and likewise, any reports best embodied in visual form may be transmitted by the operator or pilot to the central station.

Thus, for instance, where in military operations, reconnaissance flights must be made to points far removed from the main base, wherein in the return trip may take several hours, it may be extremely important that the pilot or observer be able to transmit charts or other visual reports immediately after the making of the same so that any possible information obtained in such a flight might not be lost, owing to difficulties during the return.

Likewise, the transmission of a chart or further visual instruction to a pilot far removed from his main base may best be facilitated by the use of facsimile equipment of the type herein described.

One of the essential elements of the present

invention therefore is the embodiment in a simplified unitary light-weight mechanism of facsimile transmitting and receiving media.

Still another essential object and purpose of the present invention is the utilization of the same mechanism and apparatus to operate both the facsimile transmitting and receiving media.

Another object of the present invention is the arrangement of the elements and parts of the duplex facsimile transceiver so that the operation thereof will essentially be automatic.

Still another object of the present invention is the arrangement of the transmitting and receiving elements of the unitary duplex member in such a way that actually no adjustment thereof is required to change from facsimile transmission to facsimile reception; the only important adjustment being that of changing from a receiving to a transmitting channel or means.

The present invention is primarily concerned with the actual facsimile transceiver itself and the means by which the signals generated are actually transmitted can, of course, be varied to suit the particular purpose.

Thus, for mobile units, such as automobiles, boats and airplanes, radio may furnish the best channel of transmission while for semi-portable units such as those which are to be either semi-permanently or permanently installed on land, or those which are to be carried about by an individual, means for connecting inductively or in any other way to telegraphic or telephonic circuit may be utilized.

In order to accomplish these primary objects of the present invention, I have found that both the receiving and transmitting drum and scanning elements thereof may be operated by the same mechanical elements without the necessity for any substantial adjustment (except for the change from a radio or electrical signal transmitting means to a receiving means).

The present invention may obviously be used not merely for transmission from a central base point to the mobile unit and the receivers but also for transmission and reception between mobile units for various purposes, the utility of which is quite obvious.

Essentially, the invention consists of the arrangement of transmitting and receiving drums so that that may be operated from a single power source contained within a single duplex unit and the arrangement of means for transmitting variations in light modulation and the means for receiving the same, also unitarily.

operable within a single unit and by a single mechanical apparatus. The transmitting and receiving drums are so arranged that they are readily accessible from the front or top of the unit, and the only operation actually required by the user is to place the sheet to be transmitted on the transmitting drum and the recording sheet on the receiving drum and switch his apparatus either to transmitting or receiving facilities for the purpose of operating the mechanism. Actually no further operations are required.

Many other objects and uses of the invention will in part be apparent and in part pointed out in the following description and drawings, in which:

Figure 1 is a view in perspective of a complete facsimile transceiver.

Figure 2 is a top plan view of the unitary duplex unit of the present invention with the cover of Figure 1 removed.

Figure 3 is a cross-sectional view taken on the line 2—3 of Figure 1.

Figure 4 is another cross-sectional view taken on line 4—4 of Figure 1.

Figure 5 is a top cross-sectional view taken on line 5—5 of Figure 3.

Figure 6 is a cross-sectional view taken on line 6—6 of Figure 3.

Figures 7, 8 and 9 are cross-sectional views taken on line 7—7 of Figure 6.

Figure 10 is a cross-sectional view taken on line 10—10 of Figure 2.

Figure 11 is a cross-sectional view taken on line 11—11 of Figure 2.

Figure 12 is a cross-sectional view taken on line 12—12 of Figure 2.

Figure 13 is a cross-sectional view taken on line 13—13 of Figure 2.

Figure 14 is a detail view of a portion of the transmitting scanning apparatus.

Figure 15 is a detail view of the recording scanning apparatus.

Referring now to Figure 1, I have here shown my facsimile transceiver or duplex unit comprising a transmitting drum 20, a receiving drum 21 and an outer covering 22.

It will be noted that both the transmitting and receiving drums are readily accessible from the outside of the unit for immediate use by the operator thereof. The transmitting drum 20 may readily be removed by the release of the securing means 23 hereinafter described for the purpose of wrapping a picture to be transmitted about the same, and the receiving drum 21 comprises securing means hereinafter more completely described for securely wrapping a recording sheet about the drum 21. As may readily be seen, it is not necessary to remove the receiving drum 21 in order to wrap a recording sheet about the same, while the transmitting drum may readily be removable for this purpose. In particular adaptations of my device it may be possible to make both the recording and transmitting drums readily removable in exactly the same manner or it may be possible to make both the transmitting and receiving drums permanently positioned in the apparatus.

Preferably, as seen in Figures 3 and 4, the apparatus comprises a cast iron base 25, upon which the parts may be securely supported and providing sufficient stability and steadiness for the device itself to preclude the transmission of vibrations from various parts of the mechanism through the base to other parts thereof. The

size, proportions and weight of the base itself may readily be varied in view of the particular use to which the duplex device is to be put.

For mobile work in such cases where reduction of weight is an important factor and where detailed accuracy or clarity may be to some extent sacrificed to lightness in weight and ready portability, the size and weight of the base 25 may be varied accordingly.

The motor 26 is mounted on the base 25 by means of bolts 27, securely positioned in a platform 28 carried by the base 25. The motor 26 may be maintained in generally synchronous operation with the motor of the remote transmitting or receiving device by various means which are now well known in the art, such as synchronous motors, D. C. motors in combination with fly wheel, or tuning forks, the essential element being that the motor rotates at a predetermined speed which is to be maintained as closely as possible at the constant speed.

The synchronizing mechanism hereinafter described will compensate for any possible slight variations in the speed of rotation of the motor 26 with respect to the motor of the remote transmitting or receiving device but in order effectively to operate the duplex unit, the motor should be maintained as closely as possible to the predetermined speed.

The motor 26, Figure 4, is connected by the clutch 35 to the main drive shaft 36, which drive shaft 36 projects out of the housing through the perforation 37, see Figures 1 and 4, and terminates in a handle 38. The drive shaft 36 comprises spiral gears 39 and 40 which are mounted thereon in any suitable manner and which are arranged coaxially and concentrically therewith.

Spiral gear 39 cooperates with gear 42 which is mounted on the shaft 43, which, as is seen in Figure 2, drives the transmitting drum 20. Spiral gear 40 cooperates with gear 44 mounted on the sleeve 45 which operates the receiving drum 21. Suitable housings 48 and 49 may be placed about these spiral gear and gear connections in order to, as far as possible, dust-proof the same and also in order to provide suitable bearings at 50 and 51 for the shaft 43 and at 52 and 53 for the sleeve 45.

It must be noted that, as seen in Figure 5, the sleeve 45 is preferably made of insulating material for purposes hereinafter described. Suitable removable cover plates 60 and 61 may be mounted on the housings 48 and 49 by means of the screws 63 and 64 to permit access to the interior thereof for repair or replacement of any portion of the spiral gear and gear combinations.

The transmitting drum shaft 43 is rotatably carried not only in bearings 50 and 51 but also in bearing 70 in the end wall 71 of the housing 22 and in bearing 72 of a rise 73 of the base 25. Shaft 43 terminates at the opposite side of the bearing 72 in a tail stock 74 and a disk 75, the disk 75 being keyed to the shaft 43. Disk 75 carries mounted thereon a pin 76 for cooperating with and driving the transmitting drum 20.

The transmitting drum 20 is preferably hollow, the drum having the general interior conformation shown in Figure 6 and comprising two ends 80 and 81, each of the ends having an indented or perforated portion 82 and 83 for cooperating with the tail stock 74 and the tail stock 90 of the securing device. The end 80 of the drum has a perforation 84 for receiving the pin 76 when the transmitting drum is mounted on the device so that the transmitting drum 20 is driven by shaft

43 by means of the pin and perforation connection 76-81 between the shaft 43 and the drum 20. The opposite end 81 is releasably supported by means of the removable tail stock 90 which engages the perforation 83. The removable tail stock 90 is, as seen in Figures 1 and 5, mounted upon the swingable member 95 which is pivotally mounted on a pin 96 and retained in place upon the pin by the cap 97.

The swingable member 95 comprises an enlarged portion 98 within which is mounted the tail stock 90. The opposite end of the swingable member 95 terminates in a bifurcated portion 99 for cooperating with the locking member 100, see Figures 1, 5 and 13. The locking member 100 comprises a link 105 rotatably mounted by means of the collar 106 on the pin 107 which is carried by a rise 108 of the main frame 25, the link 105 being maintained in predetermined position by the fact that it rides in a close fitting recess 109 in the frame portion 108. The link 105 terminates at the upper portion thereof in a washer 115 which is secured in any suitable manner to the top of the link, as, for instance, by the screw 116. The hollow cylindrical slide member 117 having a top 118 and flanges 119 at the bottom thereof, as well as a perforation 120 through which the link may pass, is mounted upon the link in the manner shown in Figure 13. A compression spring 125 is mounted between the washer 115 of the link and the flanges 119 of the outer hollow cylindrical member 117 and exerts pressure therebetween in such a manner as to tend to drive the flanges 119 downwardly upon the link and hence in such a manner as to drive the entire member 117 down upon the link.

When the perforation 82 of the drum 20 is mounted upon the tail stock 74 and the perforation 81 is caused to register with the pin 76, then the swingable member 95 may be moved from the position shown by the dotted lines of Figure 5 over to the position shown by the solid lines thereof. In such case then the locking device 100 may be swung up about the pin 107 and caused to engage the bifurcated end 99 of the swingable member in the manner shown in Figure 13. That is, for the purpose of locking the swingable member in place, the hollow cylindrical portion 117 may be grasped and pulled away from the mounting of the link, thus making it possible to swing the link up to the position shown in Figure 13, and then a release of the hollow cylindrical member 117 will permit the spring 125 to drive the hollow cylindrical member downwardly in the manner hereinbefore described so that the bottom end thereof presses against the bifurcated member 99 and holds the same in place. Obviously, in this operation the link passes into the space 130 between the tines of the bifurcated end 99, and the bottom portion of the hollow cylindrical member 117 presses down upon the top of the bifurcated end 99. In this way, the tail stock 90 is swung into engagement with the perforation 83 at the other end of the drum and the transmitting drum is rotatably supported at both ends.

The drive from the main shaft 36 of the motor is then completed to the transmitting drum; that is, the main shaft 36 through the worm 39 drives the gear 42 which in turn drives the shaft 43 which rotates the disk 75.

The rotation of the disk 75 through the pin 76 communicates rotative motion to the transmitting drum 20 by its engagement with the perforation 81 in the end thereof, thus resulting

in rotation of the transmitting drum in accordance with the operation of the motor. Obviously, the transmitting drum therefore may readily be removable from the transceiver to permit wrapping of any subject matter which is to be sent thereupon and the securing of such subject matter thereupon in the manner hereinafter described.

After the drum is placed into the unit in the 10 position in Figures 1 and 5 in the manner hereinbefore described, then the unit is ready for transmission.

The same type of connection may generally be utilized for the receiving drum so that it may 15 readily be removable where desired, although this is not essential, it being necessary merely to provide means for securing the recording paper upon the receiving drum without necessarily removing the receiving drum from its mounting 20 on the device.

The receiving drum is driven through the sleeve 45, which is not directly connected to the receiving drum. Essentially, this is done for the primary reason that the receiving drum should be 25 mechanically isolated by means of a friction clutch, from the remainder of the driving mechanism for the synchronizing purposes herein-after described.

As is seen in Figures 2 and 5 the receiving drum 30 is mounted upon the shaft 150 which is rotatably carried in bearings 151, 152 and 153. The sleeve 45 carries keyed thereto in any suitable manner as by the screw 160, the clutch plate 161 of the clutch 162. The plate 163 of the clutch 162 is 35 slidably mounted upon the shaft 150 in such manner that rotation thereof will result, however, in rotation of the shaft 150 owing to the registry of the slot 164 of the hub thereof with the pin 165 of the shaft 150. A compression spring 166 is 40 captured on the sleeve 167, which is secured to the shaft 150 in any suitable manner as by a pin 168, by the engagement of said spring 166 between the nut 169 adjustably mounted upon the sleeve 167 and the end 170 of the hub of the plate 163.

45 The spring pressure between the adjustable fixed nut 169 and the end 170 of the hub forces the plate 163 of the friction clutch into frictional engagement with the frictional surface 179 between the plates 161 and 163.

50 Consequently the motor 26 drives the receiving drum 21 by means of drive shaft 36 which through the spiral gear 40 is connected to the gear 44 which rotates the hollow insulated shaft 45 which through the friction clutch 162 rotates the shaft 150 upon which the receiving drum is mounted.

The receiving drum 21 is electrically grounded in the frame of the device while the recording stylus, hereinafter described, is connected to the 60 opposite terminal of the electrical circuit for the purpose of passing a current from the stylus through the recording paper to the receiving drum in order to produce markings on the recording paper corresponding to the intensity of the current passing therethrough.

65 As will be noted in Figures 2 and 5 the receiving drum preferably is a hollow member comprising end pieces 180 and 181 to which is secured the outer surface 191 of the drum and which comprises hubs 192 and 193 for securing the drum and suitable fastening means such as the screws 194 and 195 for connecting the receiving drum 70 to the shaft 150.

In order to provide for an effective translation 75 of light modulations into electrical impulses suit-

able for transmission by wire or radio, the scanning device 200 (Figures 2, 3 and 5) is arranged to traverse the transmitting drum while it rotates. Thus preferably for ordinary scanning purposes for picture transmission work, the scanning device should comprise a pencil of light of approximately $\frac{1}{100}$ of an inch in diameter and amplitude variations of this pencil of light in accordance with the lights and shades of the picture being transmitted are translated into corresponding electrical impulses.

Accordingly, the scanning device 200 should be arranged in such a manner that the pencil of light therefrom will impinge upon the surface of the transmitting drum and move along the drum $\frac{1}{100}$ of an inch during each revolution of the drum so that the picture variations will be translated into corresponding electrical impulses along a continuous spiral path $\frac{1}{100}$ of an inch wide on the transmitting drum.

In order further to maintain the correlation of the movement between the scanning device 200 and the transmitting drum 20, it is preferred that the drive of the scanning device be mechanically interlocked with the drive of the transmitting drum and actually that it be a function of the rotation of the drum.

Accordingly, as is seen in Figures 2, 4 and 5, the scanning device 200 is driven by a screw 210 formed upon the shaft 211 which is rotatably carried in bearings 212 in the side walls or frame of the machine. The shaft 43 which drives the transmitting drum 20 carries at one end thereof a gear 215 keyed thereto and rotatably therewith. Gear 215 meshes with and drives the spiral gear 216 which is keyed to and mounted upon the shaft 217 thus rotatably driving the shaft 217 in its bearings 218 and 219, which, as is seen particularly in Figure 2, are mounted upon the side walls or frame of the device. The opposite end of the shaft 217 carries a worm or spiral gear 211 which meshes with a similar gear 314 upon the shaft 211 thus in turn driving the screw 210 and causing the scanning device 200 to travel in accordance with the direction of rotation of the screw 210. By the proper arrangement of gear ratios and by the proper arrangement of the diameter of the screw 210 and the pitch thereof, the scanning device 200 may be caused to travel laterally along the transmitting drum 20 in the desired path and at the desired relative speed to effect the spiral scanning path above described due to the concomitant rotation of the drum 20.

Referring now more particularly to Figures 2, 3, 5 and 14, the scanning device 200 comprises a main base or platform 220, said main base or platform comprising preferably a main front support bar 221 and a lateral support bar 222. The lateral support bar 222 is perforated at 223 to permit the passage therethrough of the screw 210 and the shaft 211. The perforation 223 is preferably of slightly larger diameter than the greatest diameter of shaft 211 or screw 210. The front support bar 221 comprises also a tubular opening 225 therein, to permit the passage therethrough of stationary bar 226.

The stationary bar 226 is fixedly mounted at 227 and 228 in the side walls of the frame 25. The stationary bar 226 cooperating with the tubular opening 225 serves to slidably support the main platform 220 of the scanning device 200 during its scanning movement. The opposite side of the scanning device 200 is supported as is more clearly seen in Figures 2, 3 and 12 by the rollers 230, 231 and 232, these rollers registering with the

top and bottom respectively of the stationary rectangular bar 235.

The stationary rectangular bar 235 is fixedly supported between the side walls of the main frame by means of screws 236-237, passing through perforations therein so that the rectangular bar 235 is fixedly held in the lugs 238 and 239. The roller 232 is rotatably mounted, as is seen in Figure 12, on the pin 245 which is journaled in the bearing 246. The bearing 246 is rotatably captured at the end 247 of a screw member 248.

The journal 246 is rotatable with respect to the screw 248 and is therefore so arranged that it will align itself parallel to the path of movement of the scanning device 200 and accordingly will, during the movement of the scanning device 200 lie along the top of the fixed rectangular bar 235.

20 The screw 248 provides for an adjustable mounting of the bearing 246 with respect to the rectangular bar 235. The screw 248 is rotatable in the threaded perforation 252 of the rear end 253 of the portion 222 of the platform 220 and hence rotation thereof will cause the screw 248 to rise or fall, thus making the roller 232 adjustable with respect to the platform and making its engagement with the top of the rectangular bar 235 adjustable.

30 A lock nut 254 is utilized to lock the adjustment, once it has been made, in place. Rollers 231 and 230 are rotatably mounted on pins 260 and 261 in the bearings 262 and 263 which are spring biased by the leaf spring 265 towards the under side of the rectangular bar 235. The leaf spring 265 is fastened to the rear end 253 of the platform 220 by means of screws 266 and 267.

Accordingly, by this means, the rear end of the platform 220 of the scanning device 200 is resiliently but positively in slidably, frictionless engagement with the rectangular bar 235 which serves to guide it. The front end is supported by the shaft 226. The length of the opening 225 in front of the platform 220 cooperates with the shaft 226 particularly when the shaft closely approaches in diameter the size of the opening 225 to position the scanning device against any twisting or torque which may occur owing to any unevenness in the lateral movement thereof.

40 The screw 210 serves, in addition, to fixedly arrange the scanning device so that its path of movement will necessarily be parallel to the transmitting drum 20 and so that any tendency for the scanning device to twist even slightly will be completely obviated. The screw 210 serves, in the manner hereinbefore mentioned, as the motive power for the scanning device 200, rotation thereof causing a constant lateral movement of fixed degree of the scanning device 200 in fixed relation to the transmitting drum 20.

50 The scanning device itself comprises a light source 270 preferably an electric bulb, suitably removably mounted in a socket 271 (Figure 3). The socket 271 is vertically adjustable by means of the mounting thereof on the shaft 272 which is in threaded engagement with the journal 273 so that rotation of the knurled knob 274 will cause the socket to rise or fall vertically to bring the light source 270 in alignment with the optical system.

60 The socket 271 is also mounted upon a slidable platform 278 which is, as more particularly seen in Figure 2, slidable in trackways 279 and 280 which are attached to the flange 281 which in turn by means of screws 282 and 283 is fastened

to the front 221 of the main platform 220 of the scanning device 200.

The horizontal position of the light source 270 with respect to the optical system may be readily adjustable horizontally by means of the knurled screw 290 which is freely rotatably mounted in the opening 291 in the front 221 of the main platform and which is fixed against longitudinal movement by the cooperation of the knurled knob 292 and the fixed stop 293. The end of the screw 290 is at 294 in threaded engagement with a flange 295 of the socket carrying platform 278 so that rotation of the screw 290 by reason of the fact that the screw itself is fixed against longitudinal movement will result in forward or backward movement of the socket carrying the platform 278, thus resulting in an adjustment of the light source 270 with respect to the optical system.

As is seen more particularly in Figure 3, the light source 270 is preferably enclosed by a shield 300 having an opening 301 which registers with the main tube 302 of the optical system. By means of a suitable lens system comprising a lens mounted at 303 (Figures 2 and 3), the light from the light source is concentrated into a pencil of light preferably .01" in diameter at the point 304 (Figures 2 and 5), where it comes in contact with the transmitting drum 20.

A means 122 for translating light impulses into electrical impulses, such as a photoelectric cell, is mounted on the forward projection 123 of the scanning device platform 220. An additional optical system 124 comprising at least the lens 343 is so arranged (Figure 2) that the reflected light from the transmitting drum 20 is concentrated by the optical system 124 upon the photoelectric cell 122 to translate the light modulations into electrical modulations suitable for transmission by a telephone, telegraph, radio or in any other suitable manner, in a manner now well known in the art, the signals being transmitted by any of these media in various ways now known to the art as for example shown in my U. S. Patent No. 2,047,863, filed July 14, 1936.

The engagement of the scanning device with the driving screw 210 is a releasable one, as is seen particularly with reference to Figure 14. That is, the side portion 222 of the scanning device platform 220 has a perforation therein 310 of a suitable size to permit the free passage of the screw 210 and the shaft 211. The spring mounted lever 311 which is rigidly attached to the side 222 of the platform 220 so that it will not have any relative horizontal movement with respect thereto actually serves to translate the rotary movement of the screw 210 into lateral movement of the scanning device 200.

The lever 311 is rotatably mounted on the pin 312 which is securely affixed to the side member 222 of the scanning device. The lever 311 is restrained from longitudinal movement along its shaft 312 by being mounted either in a suitable annular recess of the shaft 312 or by any suitable washer or other retaining means which, however, should be of such a nature as to result in a rigid lateral connection between the lever 311 and the side member 222 so that any lateral movement imparted to the lever 311 will immediately result in corresponding movement of the entire scanning device.

A spring 315 is caught at one end on the pin 316 of the side member 222 and is wound about the pin 312 terminating at the opposite end 317 beneath the lever 311 in such position that the bias of the spring is translated into an upward

movement of the lever 311. The notch 320 in the lever 311 is threaded so as to correspond to the thread of the screw 210. The spring 315 causes the notch 320 of the lever 311 to be pressed against the screw 210 so that rotary movement of the screw 210 will result in lateral movement of the lever 311 and corresponding lateral movement of the scanning device platform 220 and, of course, corresponding movement of the scanning device 200.

It will be noted, particularly from Figure 14 however, the engagement of the lever 311 with the screw 210 is a releasable one and this release may be obtained by means of the push pin 325. The push pin 325 is mounted in a perforation 326 of a lug 327 extending from the side member 222. The perforation 326 is of sufficient length so that the push pin 325 is maintained substantially vertically. The lower end 329 of the push pin 325 abuts against the top surface of the lever 311.

A pin 330 or other suitable stop may be provided beneath the lug 327 to prevent undesired or accidental removal of the push pin 325 from the device. The opposite end of the push pin 325 terminates preferably in a knurled knob 330 which as is seen in Figure 1, projects through the slot 331 in the top of the outside cover of the machine.

Depression of the knurled knob 330 of the push pin 325 results, as is shown in dotted lines in Figure 14, in a disengagement of the scanning device from the screw 210 so that the scanning device may be slid to any desired position. For instance, when it is desired to receive impulses on the receiving drum 21, it is not necessary or even desirable for the scanning device to operate. Accordingly, depression of the knob 330 of the push pin 325 will permit a sliding of the scanning device 200 to one end or the other of the shaft 211 so that the notch 320 will be out of engagement with the screw 210 and accordingly there will be no power connection between the shaft 211 and the scanning device 200, and accordingly, therefore, the scanning device will remain stationary with respect to the transmitting drum and will not operate.

The lateral movement of the receiver-scanner device is obtained in substantially the same way.

Referring more particularly to Figures 2, 4 and 10, the shaft 150 of the receiving drum 21 carries at one end thereof fixedly mounted thereon and rotatable therewith a gear 340. The gear 340 meshes with the idler 341 which in turn meshes with the gear 342 which is fixedly mounted upon and rotatable with the shaft 343 which carries the screw 344 which in turn drives the receiver-scanning device.

As is seen most particularly in Figure 15, and as may be seen in Figures 2, 3 and 5, the receiving-scanning device 350 comprises a main carrying platform 351 of insulating material having side flanges 352 and 353. The stylus carrying rod 354 is pivotally mounted on the pin 400 which is passed through perforations in the flanges 352 and 353.

As will be noted particularly in Fig. 15, owing to the insulation construction of the main platform 351 and its associated flanges, the stylus is electrically isolated from the remainder of the mechanism.

The stylus carrying rod 354 carries preferably upon the upper surface thereof, contact carrying means comprising an angular lug 356, one flange of which preferably is fastened by rivet or screw

357 to the stylus carrying rod 354 and the other flange of which carries an adjustable screw 358 or other locking or securing device for creating and maintaining an electrical contact between the wire 359 and the stylus carrying rod 354.

The stylus carrying rod 354 carries at the front end thereof the stylus 365 which is mounted in the bifurcated front end 366 of the rod 354 by means of the screw 367. The stylus itself is adjustable both as to angle and depth of mounting, in the bifurcated end 366 of the rod 354. The stylus 365 comprises preferably a main portion 370 and an impulse transmitting needle head 371. The stylus head 371 preferably is .01" in diameter or less, in order that an electrical impulse of diameter corresponding to that of the transmitted impulse be recorded upon the paper.

The base or main insulating platform of the stylus recording mechanism comprises a perforation 375 having journals 376 at at least one side thereof in order to receive the mounting rod 377. As is seen in Figure 5, the mounting rod 377 is fixedly arranged in the riser 13 of the frame on one side and in the side wall member at the other side, and provides a slideable support for the stylus platform 351.

As is also seen in Figures 3 and 15, a rail or flange 380 is mounted on the riser 378 of the main frame by screws 388 or in any other suitable manner so that it projects upwardly to a position adjacent the stylus platform 351.

Spring 381 is secured at 382 to a pin 383 mounted on the frame 353 of the stylus platform 351 and at the opposite end at 384 abuts the rear side of the flange or guide 380. Thus spring 381 wound about the journal 376 serves therefore, by this engagement, to cause the stylus platform 351 to rotate about the shaft 377 and thus to drive the stylus head 371 towards the receiving drum 21 and the opposite end 390 of the stylus platform against the screw 344.

The opposite end 390 of the stylus platform 351 is notched at 391 and threaded in a manner corresponding to the threads of the screw 344 so that when under the bias of the spring 381, the notched portion 391 is driven against the screw 344, there is a driving engagement between the shaft 343 and the stylus platform 351.

Rotation of the shaft 343 through this power transmitting connection, therefore, results in lateral movement of the stylus platform 351 and of the entire receiver-scanning device 350. In order, therefore, to engage the receiver-scanning device 350 so that it will operate to transmit impulses along a helical path to the recording paper on the recording drum 21, it is necessary merely to raise the stylus head and slide the stylus platform 351 along the shaft 377 until the stylus head 371 is in proper relation with the boundary of the receiving drum 21 and then to release the stylus head 371 whereupon the spring 381 will automatically connect the stylus support 351 to the power transmitting mechanism to obtain the necessary lateral movement for reception.

In order to provide for any resilient adjustment that may be necessary and for a more delicate adjustment, the stylus carrying rod 354 is rotatably mounted on the pin 400 which is carried between the flanges 352 and 353. A spring 401 is captured at 402 in a perforation 403 of the flange 353 and is wound about the pivot pin 400. The opposite end of the spring is, at 404, engaged with the top of the stylus-carrying rod 354 and the spring therefor is so arranged that it is biased to drive the bifurcated end 366 of the

stylus-carrying rod 354 downwardly and hence to drive the stylus head 371 against the recording paper upon the receiving drum.

As is more clearly seen in Figure 3, the main platform 351 of the stylus scanning device is arranged to limit any downward movement of the stylus carrying rod 354 with respect thereto. The rail or flange or other guiding means 380 is necessary merely for the purpose of providing a purchase or support for the spring 381, whatever the position of the stylus may be, and hence any other suitable medium may be used as, for instance, a rod mounted in a similar position.

Where the friction between the end 384 of the spring 381 and the rail 380 or other such sliding member may become too great, a suitable roller or other friction reducing means may be provided on the end 384 of the spring. By this means, therefore, the receiving-scanning device and its stylus may be connected or disconnected from power transmitting connection with the shaft 343 and placed in a position at one end or the other of the receiving drum where it will not effectively record any impulses whatever. Likewise, and in a similar manner, the stylus may be placed appropriately for recording; and the lateral feed, by means of the screw 344 may be utilized to obtain the necessary helical scanning operation.

The stylus head 371 may have any suitable conformation and be made of any suitable material for transmitting the received electrical impulses to the recording paper. Owing to the fact that preferably a recording paper is to be used, the stylus head 371 will preferably be rounded off so as not to snag, catch or otherwise disturb, tear or distort the paper. However, by the present novel construction, any necessity for such particular treatment of the stylus head may well be obviated particularly by reason of the fact that the motion of the stylus with respect to the paper is a trailing one.

While normally in many of the prior stylus recording devices, the stylus is held against the paper in such manner that the axis of the stylus is perpendicular to any tangent drawn to the paper at that particular point; in the present stylus, the action of the stylus itself is a trailing tangential one, normally permitting the stylus to ride over any irregularities and normally tending to overcome any unevenness in the operation thereof. This is particularly so since the stylus is spring supported by means mainly of the spring 401 as well as also by the spring 381 so that it may give or rise to any irregularity in the surface of the paper or to any other snagging condition which may occur in operation.

By this novel mounting of the stylus, therefore, and the novel arrangement of the angle of the stylus with respect to the paper, it is necessary, therefore, only to make sure that the bearing surface of the stylus does not exceed the width of any particular scanning line and further to make sure simply that the bearing surface of the stylus is sufficiently smooth to avoid any snagging or tearing of the paper, keeping in mind that the motion of the stylus is a trailing, tangential one.

The particular arrangement of springs for causing the stylus to maintain proper contact with both the driving means and the recording means may be varied as circumstances require. Thus, for instance, any suitable spring may be placed, if desired, between the platform 351 and the stylus carrying rod 354 in order to bias the

stylus carrying rod into engagement with the paper. Or the stylus-carrying rod may, in a suitable embodiment, itself consist of a leaf spring with suitable adjustable stops being arranged thereabouts in order to limit the necessary movement thereof.

The means for engaging the stylus carrying platform 351 with the screw 344 of the shaft 345 may itself be varied. Thus, for instance, instead of utilizing a spring of the type of the coil spring 381, the rail or guide 380 may itself be modified to constitute a spring member or a spring biased member for holding the end 380 of the stylus-carrying platform in engagement with the screw 344. And accordingly, therefore, the raising of the stylus-carrying platform 351 will cause the spring or spring biased member substituted for the rail 380 to be shifted temporarily out of position during the disengagement.

The stylus scanning device 350 is driven not from the main drive of the motor, but from the shaft 150 upon which the receiving drum 21 is mounted. Its movement is exactly in accordance with the movement of the receiving drum 21 and any variation in movement of the receiving drum results in a corresponding variation in the movement of the stylus scanning means 360.

Impulses are detected and simplified by any suitable receiver, and conducted to the stylus and therefrom through the recording paper into the recording drum to produce a record corresponding to the received impulses employing suitable recording paper in the manner described more specifically in my application Serial No. 240,675 and 266,709.

When the device is set for transmission, that is, when a picture or other matter to be transmitted is wrapped about the transmitting drum 21 and the transmitter-scanning device 200 is, by means of the push button knob 338 moved to its proper position, then a suitable synchronizing signal may be sent, preferably once during each revolution of the transmitting drum as for example described in my U. S. Patent No. 2,047,863.

This synchronizing impulse, preferably is sent during that moment when that portion of the transmitting drum 20 which does not contain any picture to be sent passes in front of the scanner. Accordingly, the synchronizing impulse is sent preferably when the fastening means is in front of the transmitting scanner or during the interval between the two edges of the picture which is sent.

As is seen in Figures 3 and 5, a cam switch 500 is suitably mounted in an insulating block 501 which is supported by screws 502, 503, or in any other suitable manner upon an angle iron 504 fastened in any desired manner to the main frame. The cam switch comprises a central contact 510 and two auxiliary contacts 511 and 512.

When the central contact 510 is in engagement with auxiliary contact 512 (Figure 3) then the ordinary picture impulses from the photoelectric cell 310 are transmitted. Central contact 510 is thus normally arranged so that it is in engagement with contact 512. Cams 514 and 515, Figures 3 and 5, are mounted upon the shaft 43 of the transmitting drum and are so arranged that an enlarged portion thereof will abut the central contact 510 once during each revolution of the transmitting drum. The enlarged portion of the cams 514 and 515 normally coincide in circumferential position with the fastening means of the transmitting drum herein described.

When the enlarged portion of the cams 514 and 515 engage central contact 510, it breaks the connection between contacts 510 and 512, thus breaking the connection between the photoelectric cell 122 and the transmitting apparatus and makes the connection between contacts 510 and 511, thus connecting into the transmitting circuit any suitable synchronizing impulse which may be used.

Synchronization at the receiving end may be obtained in any suitable manner including any of the various methods now known and shown in my above referred patents and applications.

I have, however, illustrated one type of synchronizing means which may be utilized for this purpose.

Plate 163 of the friction clutch 162 (Figures 5 and 11) comprises a projection or hook 600. Plate 163 is, of course, keyed to the shaft 150 so that when the hook 600 strikes any impediment such as, for instance, the end of the lever 601, then the rotation of shaft 150 and the corresponding rotation of receiving drum 21 will be stopped. Owing to the fact that the engagement between the plates 161 and 163 is a frictional one, this stopping of the rotation of plate 163 and of the rotation of the shaft 150 will not prevent continued operation of the motor 26 and rotation of the plate 161.

As soon as the lever 601 is removed from engagement with the hook or stop 600 of the plate 163, then the frictional engagement between the plates 161 and 163 will result in the immediate engagement of the receiving drum 161. Lever 601 is pivotally mounted on the shaft 602 and is normally spring biased into tangential engagement with the surface of the plate 163. The bottom end of the lever 601 carries an armature 603. Electro-magnet 604 is so arranged that when energized, it will attract the armature 603 and cause rotation of the lever 601 about a pivot 602. Such attraction of the armature 603 will release the engagement between the hook or stop 600 and the end of the lever 601 and permit further rotation of the plate 163 and consequently of the shaft 150.

During each revolution of the receiving drum 21 and therefore of the plate 163, the hook or stop 600 comes into contact with the end of the lever 601. The synchronizing impulse, when received, energizes the magnet 604 to attract the armature 603 of the lever 601 and hence to release the lever 601 from its engagement with the hook and permit continued rotation.

As is further seen in Figure 10, the shaft 150 of the receiving drum also carries the cam 610 which carries the projection 611 thereon. Projection 611 cooperates with the cam switch 612. Cam switch 612 comprises switch members 613, 614 and 615 mounted upon an insulated block 616 which is secured in any suitable manner, as, for instance, by screws 617, 618 to the angle iron 619 which is in turn secured to the base 25.

Normally switch contact 613 is engaged with contact 615 to energize the stylus recording equipment. When the projection 611 of the cam 610 strikes the contact 613, it breaks the circuit between the contact 613 and 616 and establishes a circuit between contact 613 and 614, which circuit energizes the magnet 604.

The projection 611 of the cam is so arranged with respect to the hook 600 of the plate 163 that it establishes a circuit between contacts 613 and 614 simultaneously with the stopping of the plate 163 by the lever 601. Consequently, any

synchronizing impulse which will then be received will not be transmitted to the stylus but instead will be transmitted to the magnet 604. Energization of the magnet 604 by the synchronizing impulse will against start the rotation of the plate 163 and of the shaft 150 of the receiving drum 21 in the manner hereinbefore described and simultaneously then continued movement of the projection 611 of the cam 610 will reestablish the circuit between contacts 613 and 616, thus reenergizing the stylus recording equipment.

By this means, therefore, a channel for reception of the synchronizing impulse is established once during each revolution of the recording drum 21 and the picture signals are received and translated during the remainder of the revolution of the drum. Accordingly, gear ratios should be such that the recording drum 21 should rotate slightly (not more than 1 per cent) faster than the corresponding transmitting drum, the picture signals of which are received, to insure that the recording drum will reach the position for reception of the synchronizing impulse before the synchronizing impulse is transmitted.

The recording drum 21 is therefore momentarily halted once during each revolution thereof and upon reception of the synchronizing impulse is permitted to operate once more, all in the manner above described.

Where similar units are used, either at a central station and a mobile unit, or between mobile units, the synchronizing impulse therefore sent by means of the circuit established through the synchronizing contacts 508 (Figure 3) may be received by the magnet 604 (Figure 11) when the circuit therethrough is established by the cam 610 and contact 612 (Figure 10).

Various means may be utilized in order to wrap the picture to be transmitted about the transmitting drum and in order effectively to secure the recording paper to the receiving drum. In Figures 6, 7, 8 and 9 I have shown a preferred simplified form for facilitating the wrapping of the sheet to be transmitted about the transmitting drum.

The simplified means comprising a fastening plate 700 (Figures 6, 7, 8 and 9) mounted at one portion of the periphery of the drum parallel to the axis thereof and spring held in contact with the drum by means of springs 701, 701 engaging the under surface of the plate 700 at one end of the springs and engaging the rod 702 fixedly arranged within the drum at the opposite ends of the springs.

Accordingly, while the mounting plate 700 is secured to the surface of the drum, the securement is a yielding one which may readily be arranged to permit a raising or sliding of the plate for the purpose of securing the sheet to be transmitted to the transmitting drum.

Pins 705, 705 project inwardly from the mounting plate 700 and pass through the perforations 706 in the drum 20 into the interior of the drum. These pins may be either an integral part of the mounting plate 700 or may be secured thereto in any suitable manner. Pins 705 are releasably held between pins 710 and 711 on crank members 712 which are fixedly mounted upon the internal shaft 702. As now will readily be seen, by reason of the flexible mounting of the securing plate 700, the plate may readily be moved in order to permit the insertion or mounting of a sheet to be transmitted upon the transmitting drum while nevertheless securely affixing the

sheet to said transmitting drum for scanning purposes.

The procedure of mounting the transmitted sheet upon the transmitting drum may thus be greatly facilitated. Thus, as seen in Figure 8, the mounting plate 700 may be tilted to one side and an edge 715 of a sheet 716 to be transmitted inserted thereunder. The sheet may then be wrapped around the drum until the opposite end 717, as seen in Figure 9, may be brought beneath the opposite edge of the mounting plate. The mounting plate may then by finger pressure be twisted in the opposite direction and the opposite edge 717 of the transmitted sheet 716 be inserted beneath the mounting plate and secured thereby. The end result may readily be seen in Figure 7, where the transmitted sheet 716 is securely held in place by the mounting plate 700.

Instead of relying upon finger pressure to rotate the mounting plate from the position shown in Figure 8 to the position shown in Figure 9, the shaft 702 may readily be utilized. One end of the shaft 702 may terminate in a crank member 720. Owing to the fact that the members 712 carrying the pins 711 are fixedly secured to the shaft 702, a slight rotation of the crank 720 in one direction will cause rotation of the plate 712 and a tilting of the pin 705 in the manner shown in Figure 8, while a rotation of the crank 720 in the opposite direction will cause a tilting of the pin 705 in the manner shown in Figure 9 so that it will not be necessary to rely solely on finger pressure upon the mounting plate 700 in order to permit insertion of the end of the transmitted sheet, but a mere manipulation of the crank 720 for this purpose will accomplish this result.

Crank 720, of course, is so arranged within the periphery of the side of the transmitting drum that it will not interfere with any of the other mechanisms of the duplex transceiver.

Obviously, of course, as hereinbefore described, the transmitting drum 20 may readily be removed to facilitate the wrapping around of any transmitted sheet which is to be sent. The same system may be applied if desired with a drum which is to remain stationary and, if necessary, the same system may be utilized in connection with the receiving drum 21.

I prefer, however, that for receiving purposes an even more simplified system be utilized. Thus I provide spring garters 721 (see Figures 2 and 3) at either end of the receiving drum 21 so arranged that after the recording paper has been wrapped therearound, the garters may be placed over the paper and cause the paper to be securely affixed to the recording drum for recording purposes.

Each of the parts herein set forth has obviously been described in its preferred form and in the commercial embodiment heretofore found completely successful.

The adaptability and use of the device in mobile units cannot be over-emphasized. Thus, for two way facsimile communication between plane and plane, or plane and ground, or for two way facsimile communication between police automobiles, or police automobiles and central station, or for any other type of two way facsimile communication wherein the device must be simple in operation, light in weight and economical and inexpensive in construction, the present device solves a problem which has heretofore gone without any adequate solution.

With the present device, it is even possible to

receive and transmit the same or different facsimile records simultaneously upon a single duplex unit.

By the use of the present device, duplication of mechanical elements is avoided. The very mechanical elements which drive the transmitting drum and cause the operation thereof are utilized without any expensive switchover mechanism (mechanical or electrical) in order to drive the receiving apparatus. As a matter of fact, no such switchover apparatus is necessary at all since for reception purposes it is necessary only to wrap the recording paper about the receiving drum, make sure that the receiving stylus is engaged with its drive mechanism and connect the duplex device to a suitable receiver.

For transmitting it is necessary only to wrap the material to be sent about the transmitting drum, make sure that the scanning device is engaged with its drive mechanism at a point near one edge of the material to be transmitted, and connect the device to the transmitter. No other switchover mechanism of any kind whatever is necessary.

Perhaps the only mechanical adjustment which may at any time be required for the present machine is further to insure that the transmitting or receiving drums are at a correct position for starting. For this purpose it would be necessary merely to rotate the receiving and transmitting drums several degrees to a correct starting position.

Owing to the fact that very high gear ratios are used and owing to the fact that mechanical advantage is on the side of the motor, or rather of the motor shaft 36, and owing to the fact that the gear connections between gears 40 and 44 and gears 39 and 42 are self-locking or self-braking, it may be difficult to rotate the drums 20 and 21 by hand. Accordingly, for purposes of such adjustment the shaft 36 may, as is seen particularly in Figures 1 and 4, be extended out beyond the front of the machine to terminate in the knob 38. Rotation of the knob 38 may be utilized to shift the drums 20 and 21 several degrees in any direction which may be necessary to reach the edge of the recording or transmitting sheet before the operation is started. This is the only other mechanical adjustment which may be necessary and is utilized merely to insure that the scanning operation, whether transmitting or receiving, starts at the proper corner of the sheet.

In any proper case, where weight is not an essential factor and where absolute convenience in speed and operation is not an essential requirement, obviously a light scanning system on a sensitive record sheet may be utilized for reception. In such case a suitable shield should be provided to exclude foreign light sources from the receiving drum.

It will be noted, of course, that as far as the transmitting operation is concerned, with the present device the entire cover of the device furnishes an effective shield against the effect of any stray light upon the transmitting mechanism, particularly since whatever light is impinged upon the photoelectric cell 122 must pass through the narrow opening 130, Figures 1 and 5, in the front of the mechanism.

Accordingly, in the use of the present machine it is necessary for the airplane pilot or automobile operator or the operator in any other mobile unit, in the event he wishes to transmit any material, such, for instance, as charts or maps 73

which he may have made during the flight or trip, merely to wrap the material to be transmitted about the transmitting drum, securely fastening the edges thereof beneath the mounting plate 100 in the manner hereinbefore described; depress the push button knob 330 and thereby push the scanning mechanism over to the starting point of the scanning operation; rotate the handle 38 to make certain that the commencement of the scanning operation starts at the proper corner of the picture and then connect the duplex mechanism to his radio transmitter, make sure that connection is made with the receiving station, and commence the transmitting operation.

During the transmitting operation, the operator may, if he so desires, move the stylus of the receiving portion of the unit over to one side so that it will not traverse the receiving drum during the operation. This is not an essential movement unless the wear of the stylus head is to be avoided.

For receiving it is necessary for the operator merely to wrap a recording sheet about the receiving drum 21, securing the same in place by means of the garters 121, place the stylus head, by the method hereinbefore described, in position at one side of the recording sheet, and turn the knob 38 so that the stylus head starts its recording at one corner of the recording sheet and connect the device with the receiver of his radio or with any other suitable facsimile receiver. For this purpose, the operator may, if he so desires, move the transmitter scanner over to one side by depressing the push-button 330, but it is not essential that he do so.

In a suitable device it would be possible to utilize a single drum for both transmission or reception by maintaining the mounting of the scanning device in the position shown for instance in Figure 2 and by moving the operating shaft of the recording stylus to such position that it will cooperate with the single drum. In such case by the proper use of a friction clutch on the single drum and means for switching over from synchronizing impulse transmission operation to a synchronizing impulse receiving operation upon the single shaft of the single drum, and by proper arrangement for changing the gear ratio slightly when the friction clutch is permitted to operate for reception, a single drum may be utilized both for transmission and reception. For this purpose proper connections should be made with respect to the single transmitting-receiving drum for properly grounding the same.

Various other embodiments and uses of the present device will now be clear to those skilled in the art. Thus apart from mobile use between mobile units and mobile use between mobile units and stationary central stations, particularly in those cases, such as in light weight airplanes, pursuit ships, reconnaissance planes, small boats and light weight automobiles where weight is an important factor, the present device may well have importance in ordinary non-mobile station to station operation or station to subscriber operation.

It may well have extreme importance in alarm systems, signalling systems and communications systems of various kinds, whether portable or stationary.

With proper adaptation a continuous sheet facsimile recording system may be utilized in con-

nection with the recording portion of the duplex device.

The synchronizing impulse transmitting and receiving means may be varied to suit particular circumstances, the essential element of the present invention being that in a single unitary duplex machine both transmitting and receiving functions may be embodied in a light weight simple, readily operated form.

Many other variations in particular portions of the device may be made and many other variations in the uses to which the device may be put may now be understood by those skilled in the art all within the spirit of the present invention, the essential portion of which comprises the combination in a single duplex unit of facsimile transmission and reception apparatus without necessarily duplicating any of the mechanical elements.

Likewise many other novel uses of the various portions of the present invention will now be clear to those skilled in the art including the arrangement and operation of the transmission scanning system and reception scanning system.

I prefer, therefore, to be limited not by the specific disclosures herein but only by the appended claims.

I claim:

1. A duplex facsimile transmitter and receiver unit comprising a transmitting drum, a recording drum, scanning means individual to each of said drums, said means comprising a photosensitive scanning member operably connected to said transmitting drum and driven in synchronism therewith, and a recording element operably connected to said recording drum and driven in synchronism therewith, means including a single source of power for driving said transmitting drum at a predetermined speed and for driving said recording drum at a predetermined speed different than the speed of said transmitting drum, said drums being operable simultaneously, the transmitting drum rotating continuously and the recording drum rotating intermittently.

2. A duplex facsimile transmitter and receiver unit comprising a transmitting drum, a recording drum, scanning means individual to each of said drums, said means comprising a photosensitive scanning member operably connected to said transmitting drum and driven in synchronism therewith, and a recording element operably connected to said recording drum and driven in synchronism therewith, a power source, and power transmitting connections from said power source to said transmitting drum, recording drum and scanning means, and means in said power transmitting connections for driving said transmitting drum at one speed and said recording drum at a different speed, said drums being operable simultaneously, the transmitting drum rotating continuously and the recording drum rotating intermittently.

3. A duplex facsimile transmitter and receiver unit comprising a transmitting drum, a recording drum, scanning means individual to each of said drums, said means comprising a photosensitive scanning member operably connected to said transmitting drum and driven in synchronism therewith, and a recording element operably connected to said recording drum and driven in synchronism therewith, a power source, a drive shaft operated thereby, a power transmitting connection between said drive shaft and said transmitting drum, a power transmitting connection from said drive shaft to said recording drum, said power transmitting connections permitting the

operation of said drums at predetermined different speeds and means for driving the scanning means of said drums said drums being operable simultaneously, the transmitting drum rotating continuously and the recording drum rotating intermittently.

4. A duplex facsimile transmitter and receiver unit comprising a transmitting drum, a recording drum, scanning means individual to each of said drums, said means comprising a photosensitive scanning member operably connected to said transmitting drum and driven in synchronism therewith, and a recording element operably connected to said recording drum and driven in synchronism therewith, a power source, a drive shaft operated thereby, a power transmitting connection between said drive shaft and said transmitting drum, a power transmitting connection from said drive shaft to said recording drum, said power transmitting connections permitting the operation of said drums at predetermined different speeds, means for driving the scanning means of said drums, and a clutch between the drive shaft and the shaft of said recording drum.

5. A duplex facsimile transmitter and receiver unit comprising a transmitting drum, a recording drum, scanning means individual to each of said drums, said means comprising a photosensitive scanning member operably connected to said transmitting drum and driven in synchronism therewith, and a recording element operably connected to said recording drum and driven in synchronism therewith, a power source, a drive shaft operated thereby, a power transmitting connection between said drive shaft and said transmitting drum, a power transmitting connection from said drive shaft to said recording drum, said power transmitting connections permitting the operation of said drums at predetermined different speeds, means for driving the scanning means of said drums, a clutch between the drive shaft and the shaft of the recording drum, and means operable upon the shaft of the recording drum for intermittently interrupting the said power transmitting connection between the drive shaft and the recording drum shaft and for re-engaging said connection in response to synchronizing impulses.

6. A duplex facsimile transmitter and receiver unit comprising a transmitting drum, a recording drum, scanning means individual to each of said drums, said means comprising a photosensitive scanning member operably connected to said transmitting drum and driven in synchronism therewith, and a recording element operably connected to said recording drum and driven in synchronism therewith, a power source, a drive shaft operated thereby, a power transmitting connection between said drive shaft and said transmitting drum, a power transmitting connection from said drive shaft to said recording drum, said power transmitting connections permitting the operation of said drums at predetermined different speeds, and means for driving the scanning means of said drums, and means associated with the transmitting drum for originating synchronizing impulses.

7. A duplex facsimile transmitter and receiver unit comprising a transmitting drum, a recording drum, scanning means individual to each of said drums, said means comprising a photosensitive scanning member operably connected to said transmitting drum and driven in synchronism therewith, and a recording element operably connected to said recording drum and driven in syn-

chronism therewith, a power source, a drive shaft operated thereby, a power transmitting connection between said drive shaft and said transmitting drum, a power transmitting connection from said drive shaft to said recording drum, said transmitting and recording drums being operable at predetermined different speeds, means for driving the scanning means of said drums, a clutch between the drive shaft and the shaft of said recording drum, means operable upon the shaft of the recording drum for intermittently interrupting the said power transmitting connection between the drive shaft and the recording drum shaft and for reengaging said connection in response to synchronizing impulses, and means associated with the transmitting drum for originating synchronizing impulses.

8. A duplex facsimile transmitter and receiver unit comprising a base, a cover therefor, a source of power mounted on said base, a power shaft 20 driven from said source of power, a transmitting

drum operating shaft driven by said power shaft, a recording drum operating shaft driven by said power shaft, a transmitting drum removably mounted outside the cover in power transmitting connection with said transmitting drum operating shaft and a recording drum mounted outside the cover in disengageable power transmitting connection with said recording drum operating shaft said transmitting and recording drums being operable at predetermined different speeds, scanning means operable from the transmitting drum operating shaft and recording means operable from the recording drum operating shaft, said recording and scanning means being selectively disengageable from operative connection with the mechanism, and means operable from outside the cover for connecting and adjusting said scanning and recording means relative to their respective drums.

WILLIAM G. H. FINCH.
